UNITED STATES PATENT OFFICE.

DE WITT H. WYATT, OF COLUMBUS, OHIO, ASSIGNOR TO CHARLES A. DIVINE, OF COLUMBUS, OHIO.

DESIGN FOR A COMBINED LAMP-STANDARD AND STREET-INDICATOR.

53,550.

Specification for Design.

Patented July 8, 1919.

Application filed June 18, 1917. Serial No. 175,544. Term of patent 7 years.

To all whom it may concern:

Be it known that I, De WITT H. WYATT, a citizen of the United States, residing at Columbus, in the county of Franklin and State of Ohio, have invented a new, original, and ornamental Design for a Combined Lamp-Standard and Street-Indicator, of which the following is a specification, reference being had to the accompanying drawing, forming part thereof.

The figure represents a perspective view

of my improved lamp standard and street indicator.

I claim:

The ornamental design for a combined lamp standard and street indicator, as shown.

DE WITT H. WYATT.

Witnesses:

WALTER E. L. BOCK,
A. L. PHELPS.
